UNITED STATES PATENT OFFICE

168,603

COMBINATION DEEP FREEZER AND BUFFET UNIT

Marian M. Tell, Vallejo, Calif.

Application October 21, 1952, Serial No. 21,915

Term of patent 14 years

(Cl. D33—13)

To all whom it may concern:

Be it known that I, Marian M. Tell, a citizen of the United States and a resident of Vallejo, county of Solano, California, have invented a new, original, and ornamental Design for a Combination Deep-Freezer and Buffet Unit, of which the following is a specification, reference being had to the accompanying drawing forming a part thereof.

I claim:

The ornamental design for a combination deep-freezer and buffet unit, as shown.

MARIAN M. TELL.
